The ornamental design for earcups for a headset, as shown and described.

DESCRIPTION

FIG. 1 is a front perspective view of earcups for a headset showing the new design;

FIG. 2 is a front view of the earcups of FIG. 1;

FIG. 3 is a rear view of the earcups of FIG. 1;

FIG. 4 is a left side view of the earcups of FIG. 1;

FIG. 5 is a right side view of the earcups of FIG. 1;

FIG. 6 is a top view of the earcups of FIG. 1; and,

FIG. 7 is a bottom view of the earcups of FIG. 1.

The broken lines depict portions of the earcups for a headset that form no part of the claimed design.
